PRESSER MECHANISM FOR SEWING MACHINES

Frank A. Kucera, Chicago, Ill., assignor to Union Special Machine Company, Chicago, Ill., a corporation of Illinois

Application January 30, 1936, Serial No. 61,469

2 Claims. (Cl. 112—235)

This invention relates to presser mechanism of the type in which a vertical bar carrying the presser foot is confined to axial up and down movement in a guide head at the end of an overhanging arm of the sewing machine and yieldingly urged downward by a horizontal leaf spring. 5

In such mechanism, as heretofore constructed, the end of the leaf spring bore either directly on the top end of the presser bar, or upon a collar 10 or other fixed projection on said bar, with the result that it exerted lateral strains which tended to cause binding and sticking of said bar in the guide head.

The purpose of my invention is to obviate the difficulty to which attention has just been directed. This objective I attain in practice, as hereinafter more fully disclosed, through provision of a connecting means between the leaf spring and the presser bar capable of compensating for lengthening and shortening of said spring incident to flexing thereof so that lateral straining and binding of said bar is effectively precluded and the latter left entirely free to efficiently perform its allotted functions. 20

25 In the attached drawing, Fig. I is a side elevation of a sewing machine conveniently embodying my improved presser mechanism.

Fig. II is a fragmentary detail plan view looking as indicated by the arrows II—II in Fig. I 30 and drawn to a larger scale.

Fig. III is a fragmentary detail sectional view taken as indicated by the arrows III—III in Figs. I and II; and

Fig. IV is a perspective view of the connecting member hereinbefore mentioned. 35

The illustrated sewing machine has a hollow overhanging arm 1 which extends horizontally from an integrally-formed hollow standard 2 rising from one end of a base 3, the top surface of 40 the latter being flat and constituting a work support. Confined to axial movement in a guide head 4 at the free end of the arm 1 is a bar 5, which, at its lower end, carries a pair of needles 6 that cooperate with a looper or loopers (not shown) concealed within the hollow of the base 3. Through suitable connections likewise within the framework of the machine the needles 6 and the concealed looper or loopers are caused to function in timed relation in forming chain 45 stitches after a well known manner.

Also having guidance for axial movement in the head 4 is a vertical presser bar 7 to the bottom end of which is secured the presser foot 8 whereby the fabric being sewed is held down against the 55 top surface of the base 3 while being progres-

sively advanced by the feed mechanism (not illustrated) of the machine. The presser bar 7 is subject to a horizontal leaf spring 10 which is mounted on the top of the arm 1, and whereof the inner or right hand end is apertured to engage a fixed upstanding anchorage stud projection 11 within the recess 12 of a movable cap 13 closing an opening through which access is had into the hollow of the standard 2. The force of the spring 10 is regulatable by means of a thumb nut 14 threaded on a vertical stem 15 on the arm 1 which passes through a central aperture in said spring. Interposed between the thumb nut 14 and the top of the spring 10 is a smaller auxiliary leaf spring 16. 15

In order to prevent the imposition of binding strains upon the presser bar 7 and so preclude interference with the free operation thereof, I have made the provisions which are about to be described. 20

From Figs. I and III, it will be observed that the presser bar 7 is formed with a diametrically reduced top portion 17 whereof the end is rounded and over which is placed a stirrup-like member 18 having an outwardly projecting circular flange 19 at its bottom. As shown at 28 in Fig. III, the stirrup-like member 18 has an internal spherical recess centrally of its top engaging the rounded upper end of the presser bar 7, and as further shown, said member has an axial opening 21 of a diameter considerably larger than that of the reduced portion 17 of said presser bar. The flange 19 of the stirrup-like member 18 constitutes a bearing surface for the outer end of the leaf spring 10 which is clevised or bifurcated in accordance with my invention as shown at 22 in Figs. II and III to clear the upper portion of said member 18. 30

By virtue of the capacity for universal pivotal movement of the stirrup member 18 about the upper rounded end of the presser bar 7 lengthening and shortening of the leaf spring 10 incident to its flexing in accommodating the movements of the presser bar 7 is compensated for. Accordingly, no lateral strains will be induced in the 45 presser bar 7, the latter being thereby insured against binding within the guide head 4 and left free to move up and down as different thicknesses of fabric pass beneath the presser foot 8.

Having thus described my invention, I claim: 50

1. Presser mechanism for sewing machines and the like including a presser bar with a rounded end; a guide confining the bar to axial movement; a stirrup-like member engaged over and supported, with capacity for universal pivotal 55

movement, on the rounded end of the presser bar; and a leaf spring exerting endwise pressure upon the bar, said spring having its end bifurcated to straddle the stirrup member and bear upon a flange around the bottom of the latter.

5. Presser mechanism for sewing machines and the like including a vertical presser bar; a guide

confining the presser bar to axial movement; a leaf spring for exerting endwise pressure on the bar; and a suspension member having a universal pivot bearing with the top end of the bar and affording a rest for the free end of the spring 5 below said pivot bearing.

FRANK A. KUCERA.
